L. O. WETHERELL

DISPLAY DEVICE

Filed Dec. 9, 1922

UNITED STATES PATENT OFFICE.

LESLIE O. WETHERELL, OF ATTLEBORO, MASSACHUSETTS, ASSIGNOR TO FREEMAN-DAUGHADAY COMPANY, OF CHARTLEY, MASSACHUSETTS, A CORPORATION OF MASSACHUSETTS.

DISPLAY DEVICE.

Application filed December 9, 1922. Serial No. 605,841.

To all whom it may concern:

Be it known that I, LESLIE O. WETHERELL, a citizen of the United States, residing at Attleboro, in the county of Bristol and State 5 of Massachusetts, have invented certain new and useful Improvements in Display Devices, of which the following is a specification.

This invention relates to display devices 10 of the class adapted for use in displaying cuff buttons and other articles of jewelry, and the object of this invention is to provide a display device of this character in which individual cards on which articles are 15 mounted, are adapted to be removably held.

The invention further consists in the provision of means in said device whereby these cards or holders carrying the goods may be held in flat or extended position to render 20 the display more attractive.

A further object of the invention is to provide a cover or inclosing plate for the back of the device to inclose that portion of the articles which extend beyond the back supporting plate and to also cause the display device to present a more finished appearance to the observer when any of the holder cards are removed from the openings therein.

With these and other objects in view, the 30 invention consists of certain novel features of construction, as will be more fully described, and particularly pointed out in the appended claims.

In the accompanying drawings—

Figure 1 is a front view of my improved display device showing portions partly broken away to better show its construction.

Figure 2 is a side elevation partly in section illustrating the device as being supported in display position by a supporting standard.

Figure 3 is a rear view showing a fragmental portion of the device and partly broken away to better illustrate its construction.

Figure 4 is an enlarged section illustrating a pair of separable cuff buttons as mounted on a holder card, the card being mounted in the support and the cover plate spaced from the back to inclose the inner ends of the cuff buttons.

Figure 5 is a perspective view showing a detail of the ordinary holding card.

The following is a detailed description of

one embodiment of my invention by which 55 the desired results may be obtained, the same comprising essentially a front plate 10, preferably formed of cardboard, provided with a plurality of openings 11. On the back of this front plate, I preferably secure a spacer 60 plate 12 also having openings and adapted to register with those in the front plate, and on the back of this spacer plate I secure a back plate 13 having openings registered with those in the front plate and the spacer 65 plate, the openings in this back plate being preferably of a size greater than those in the front plate, and this back plate is preferably provided with inwardly-extending tabs or projecting portions 14 which are formed on 70 the marginal edges of the back plate to extend towards each other, preferably beyond the marginal edges of the front plate.

Any desired articles of jewelry may be mounted upon any suitable card or the like 75 to be positioned in these openings, but the card 15 shown in Figure 5 is especially adapted to receive such articles of jewelry as cuff buttons and is provided with holes 16 through which a pair of separable but- 80 tons 17 may be connected.

When it is desired to position this card with its buttons mounted thereon, in the opening 11 in the display, it is only necessary to buckle or bend the card longitudinally 85 sufficiently to enable its marginal edges to enter the contracted openings through the front plate and to carry it inwardly until those edges rest upon the tabs 14 when upon being released the card immediately springs 90 back to its normal or flat condition with its face substantially parallel to the front plate, the grooves or recesses 18 in the holder being of sufficient depth to allow this card to lie in extended position, that is, when these cards 95 are in extended position their side marginal edges extend beneath the corresponding edges of the front plate and the tabs 14 in the back plate engage the under side of the card thus releasably retaining the card in 100 extended display position.

The size of the space between the front and back plate is preferably sufficient to permit the holder card to lie in extended position.

It is found in practice that a device of this character which is adapted to permit its holder cards to lie flat, has considerable

2
advantage over one in which the cards must be raised in order to be retained therein: first, the display device is very much neater in appearance where the face of its holder card lies parallel with that of the front plate; and second, by having a holder card lie in this flat position the articles displayed do not extend forwardly above the front surface of the device so far as when mounted on raised cards, which is considered of advantage in such display card devices.

10 It is found in practice of considerable advantage for several reasons, to provide an inclosing or cover plate for housing the inner 15 ends of the cuff buttons and to accomplish this in a simple and effective way, I have provided a box-shaped member 19 having side walls 20 and end walls 21 turned up with its marginal edges turned outwardly to 20 engage and be secured to the back plate 13 of the supporting member.

25 The bottom of this box member is spaced sufficiently from the back plate to receive the inner head member of the cuff button. By 30 this construction the inner face 22 of the bottom of the box may be so finished that when one of the holder cards 15 is removed with its cuff buttons from the display device the appearance of the display is not detrimentally affected as would be the case if no backing plate were employed.

I claim:

35 1. A display device for jewelry mounted on cards, comprising front and back plates having registering openings, an intermediate member spacing said front and back plates providing a recess between them to receive the edges of the cards, said member having edge portions set inwardly from the opening 10 against which an edge of said card mounted therein may rest to cooperate with said front and back plates to retain said

cards in their display position in said openings.

2. A display device for buttons and the 45 like comprising a support for button holders having front and back plates with registering openings and spaced apart to provide slots for the reception of the edges of said holder to retain the same when the holder is in extended position, and a rear cover plate 50 spaced from said back plate a distance sufficient to receive the rear head of the button when its holder is positioned.

3. In a display device, a support for article holders comprising front intermediate and back plates having openings in registration, a holder for articles to be displayed adapted to fit within the opening in the intermediate plate, said front and back plates having portions overlapping the opening in said intermediate plate whereby said holder is retained in the opening in said intermediate plate, and a rear cover plate spaced 60 from said back plate a distance sufficient to 65 receive the rear of the article when its holder is positioned.

4. In a display device, a support for article holders comprising front intermediate and back plates having openings in registration, the openings in the front plate being smaller than the openings in the other plates, and rigid tabs extending inwardly 70 from the back plate, said tabs permitting 75 holders for the articles to be displayed to be slipped into and lie flat in the openings in the intermediate plate, the tabs thereafter retaining the holders in place, and a rear cover plate spaced from said back plate a 80 distance sufficient to receive the rear of the article when its holder is positioned.

In testimony whereof I affix my signature.

LESLIE O. WETHERELL.
